UNITED STATES PATENT OFFICE

158,577

POLISHING MACHINE HOUSING

William E. Holt, Oakland, Calif.

Application May 10, 1949, Serial No. 2,557

Term of patent 14 years

(Cl. D9—2)

To all whom it may concern:

Be it known that I, William E. Holt, a citizen of the United States, residing at Oakland, in the county of Alameda and State of California, have invented a new, original, and ornamental Design for a Polishing Machine Housing, of which the following is a specification, reference being had to the accompanying drawing, forming part thereof.

Fig. 1 is a front perspective view of a polishing machine housing, showing my new design; and

Fig. 2 is a rear perspective view of the housing shown in Fig. 1.

The dominant features of the design reside in those portions shown in full lines.

I claim:

The ornamental design for a polishing machine housing, as shown and described.

WILLIAM E. HOLT.
